RAILWAY TRUCK STRUCTURE

William H. Sale, Sandston, Va.

Application November 10, 1941, Serial No. 418,529

12 Claims. (CL 188—212)

The invention relates to railway truck structures, and more particularly to devices for supporting the brake-beams.

One object of the present invention is to provide a supporting device for the brake-beam which permits the brake-beam to be conveniently and quickly removed and installed.

Another object of the invention is to provide a supporting device for the brake-beam which includes a wear member which can be readily replaced when it becomes worn.

Another object is to provide a support for the brake-beam which eliminates the hangers now generally used.

Other objects of the invention will appear from the detailed description.

The invention consists in the several novel features hereinafter set forth and more particularly defined by claims at the conclusion hereof.

In the drawings Fig. 1 is a horizontal section of one side-frame of a truck and the supporting devices for the ends of a pair of brake-beams adjacent one of the side-frames, taken on line 1—1 of Fig. 2, the truck springs being omitted. Fig. 2 is a section taken on line 2—2 of Fig. 1. Fig. 3 is a vertical section taken on line 3—3 of Fig. 2. Fig. 4 is a perspective of the extension on the side-frame and the bracket for mounting the supporting devices for the ends of a pair of brake-beams. Fig. 5 is a perspective of the yoke which fits around the brake-beam and is slidably mounted and detachably secured in the bracket on the side-frame. Fig. 6 is a perspective of the pin for detachably holding the yoke in the bracket and securing the yoke and brake-beam together.

The invention is exemplified in a railway truck comprising a cast side-frame 10, a spring bolster 11 mounted in the side-frame, a spring plank 12 fixed to the side-frame, truck springs 13 between the spring plank 12 and the bolster 11, truck wheels 14, a pair of brake-beams, each of which includes a compression member 15, a tension or truss member 16, and a head 17 between the ends of the compression and tension members, and brake shoes 18 secured to the heads 17. All of these parts may be used with the brake-shifting mechanisms of standard construction as well understood in the art. The side-frames, brake-beams, wheels, and safety-supports for the beams, are alike in construction at both sides of the truck, as well understood in the art, so that it has not been deemed necessary to illustrate them at both sides.

Each side-frame is provided with means for supporting the ends of a pair of brake-beams. Each side-frame has an inward and transverse extension or member 20 which underlies the spring plank 12, pedestals 21 at the inner ends of member 20 and at the sides of the spring-plank, and upper and lower substantially parallel longitudinally extending arms or members 22 and 23. The upper end of each pedestal 21 may be connected to the side-frame by a web 24. Arms 22 and 23 form a guideway for slidably supporting one end of the brake-beam. Each pair of arms 22 and 23 and pedestal 21 are disposed inwardly of the outer ends of the brake-beam 17, and constitute a bracket for slidably supporting a brake-beam independently of the usual suspension links.

Each beam-supporting device comprises a yoke 25 which has a semi-circular portion 26 which fits around one side of tension or truss member 16 of the brake-beam and upper and lower members 27 and 28 which fit and are slidable between the arms 22 and 23 of the bracket on the side-frame. The compression member 15 of the brake-beam extends transversely through the forked portion of the yoke and is confined vertically between members 27 and 28. Ribs 32 are provided on arms 22 and 23 for confining the yokes 28 transversely in the bracket. A pin 30 extends through vertically aligned holes 31 in the yoke and detachably secures the yoke and the tension and compression members of the brake-beam together. Pin 30 extends through an elongated slot 31 in the upper arm 22 for sliding movement of the yoke longitudinally of the truck, and detachably connects the yoke to the bracket. Pin 30 serves as a removable key to permit the separation of the yoke from the supporting bracket. The yoke and pin constitute a clevis which is detachable from the brake-beam and detachable from arms 22 and 23. A wear-plate 23a is removably fitted on the top of arm 23.

A spring 34 is provided for shifting each end 45 of the brake-beam to its brake-releasing position. Spring 34 is coiled around a bolt 35, the inner end of which is provided with a head 36 which extends through and has a head held by the inner side of the pedestal 21. Bolt 35 extends through a hub 38 on the upper end of pin 30 which is engaged by the inner end of spring 34. A nut 37 engages the outer end of spring 34 to keep it compressed and is adapted to adjust the pressure of the spring 34. This bolt is removable from the supporting bracket so it can be

withdrawn from the pin 30 and so that the latter can be removed. When the brake-beams are shifted to apply the brake-shoes 18 to the wheels 14, springs 34 will be compressed by the usual equalizing and shifting mechanism for the brake-beams, and the yokes 25 and pins 30 will be slidably shifted in the brackets on the side-frame against the force of said springs. Each pin 30 will move with its associated yoke and end of the brake-beam. When the brake-shifting mechanism is released, springs 34 will shift the brake-beam, yokes and pin 30 toward the longitudinal center of the truck. A characteristic of this construction is that the yokes 25 serve as wear members which can be readily replaced and detached from the brake-beam upon removal of the pins 30. When the nut 37 is screwed off bolt 35 the latter can be withdrawn from pedestal 21 and hub 38 of the pin, whereupon the pin will be free to be withdrawn from the yoke. Upon removal of pin 30 as aforesaid, the yoke can be withdrawn from arms 22 and 23, and then the brake-beam can be released, so that it will not be necessary to jack up the car or remove the side-frame from the truck for repair or replacement of the safety-supporting devices. This construction facilitates repairs or replacements when such are necessary, and also facilitates assembly of brake-beam and beam-supporting devices. By removal of the yoke as before described, the brake-beams, after the brake-shoes have been removed therefrom, can be moved longitudinally to clear the brackets on the side-frames and then dropped between the side-frames. By reversing the operation, the brake-beams can be easily and quickly assembled with the bracket and the yokes, and secured in the brackets by pins 30. The springs normally hold the beams spaced away from the wheels so the brake-shoes will not engage the wheels, to avoid necessary brake-shoe wear. The supporting devices for the brake-beam render the suspension links now commonly used unnecessary.

The invention is not to be understood as restricted to the details set forth, since these may be modified within the scope of the appended claims without departing from the spirit and scope of the invention.

What I regard as new and desire to claim by Letters Patent is:

1. A railway truck structure comprising a side-frame, a brake-beam, a brake-shoe at one end of the beam, a longitudinally extending bracket carried by the side-frame transversely inward of the brake-shoe, a yoke removably fitting around the brake-beam, and slidably and removably mounted in the bracket, and means for detachably securing the yoke around the brake-beam and for retaining the yoke in the bracket.

2. A railway truck structure comprising a side-frame, a brake-beam, a brake-shoe at one end of the beam, a longitudinally extending bracket carried by the side-frame transversely inward of the brake-shoe, an open-ended yoke removably fitting around the brake-beam, and slidably and removably mounted in the bracket, and a pin for detachably securing the yoke around the brake-beam and slidably mounted in the bracket for retaining the yoke in the bracket.

3. A railway truck structure comprising a side-frame, a brake-beam, a brake-shoe at one end of the beam, a longitudinally extending bracket carried by the side-frame transversely inward of the brake-shoe, an open-ended yoke removably fitting around the brake-beam, and slidably and removably mounted in the bracket, means for de-

tachably securing the yoke around the brake-beam and means carried by the bracket for shifting the yoke and the beams into brake-releasing position.

5. A railway truck structure comprising a side-frame, a brake-beam, a brake-shoe on one end of the beam, a longitudinally extending bracket carried by the side-frame transversely inward of the brake-shoe, an open-ended yoke removably fitting around the brake-beam, the brake-beam extending transversely through the yoke and bracket, the yoke being slidably and removably mounted in the bracket, and means for detachably securing the brake-beam in the yoke and for retaining the yoke in the bracket.

10. A railway truck structure comprising a side-frame, a brake-beam having compression and tension members, a brake-shoe on the end of the beam, a longitudinally extending bracket carried by the side-frame transversely inward of the brake-shoe, an open-ended yoke having a closed end removably fitting around the tension member of the brake-beam, the compression member extending through the yoke adjacent its open end, the yoke being slidably and removably mounted in the bracket, and means for detachably securing the brake-beam in the yoke and for retaining the yoke in the bracket.

15. A railway truck structure comprising a side-frame, a brake-beam having compression and tension members, a brake-shoe on the end of the beam, an inward extension on the side-frame having a longitudinally extending bracket transversely inward of the brake-shoe, an open-ended yoke having a closed end removably fitting around the tension member of the brake-beam, the compression member extending transversely through the yoke adjacent its open end, the yoke being slidably and removably mounted in the bracket, and a pin slidably connected to the bracket for detachably securing the brake-beam in the yoke for retaining the yoke in the bracket.

20. A railway truck structure comprising a side-frame, a brake-beam having compression and tension members, a brake-shoe on the end of the beam, an inward extension on the side-frame having a longitudinally extending bracket transversely inward of the brake-shoe, an open-ended yoke having a closed end removably fitting around the tension member of the brake-beam, the compression member extending transversely through the yoke adjacent its open end, the yoke being slidably and removably mounted in the bracket, means for detachably securing the yoke on the brake-beam and for retaining the yoke in the bracket, and spring-means detachably supported on the bracket for shifting the beam and yoke in brake-releasing position.

25. A railway truck structure comprising a side-frame, a brake-beam, a brake-shoe at one end of the beam, a transversely inward extension on the side-frame, a pedestal and upper and lower longitudinally extending arms on the extension forming a bracket, an open-ended yoke removably fitting around the brake-beam and into which the brake-beam is insertable through its open end, the yoke being slidably and removably mounted between the bracket arms, and means for detachably securing the brake-beam in the yoke, slidably in the bracket for retaining the yoke in the bracket.

30. A railway truck structure comprising a side-frame, a brake-beam, a brake-shoe at one end of the beam, a transversely inward extension on the side-frame, a pedestal and upper and lower

longitudinally extending arms on the extension forming a bracket, an open-ended yoke removably fitting around the brake-beam and into which the brake-beam is insertible through its open end, the yoke being slidably and removably mounted between the bracket arms, a pin for detachably securing the brake-beam in the yoke, slidable in the bracket for retaining the yoke in the bracket, and means carried by the bracket for shifting the yoke and beam and pin to brake-releasing position.

10. A railway truck structure comprising a side-frame, brake-beams, a brake-shoe at one end of the beam, a spring plank carried by the side-frame, an integral inward extension on the side-frame underlying the spring-plank, a bracket extending upwardly from the inner end of and integral with the extension at each side of the spring-plank, a yoke fitting around and removable from the brake-beam and slidably and removably mounted in the brackets, respectively, and means for detachably securing the yokes around the brake-beams and connecting them to the brackets.

11. A railway truck structure comprising a

25 side-frame, brake-beams, brake-shoes at the ends of the beams, a spring-plank carried by the side-frame, an inward extension on the side-frame underlying the spring plank, a bracket on the inner end of the extension at each side of the spring-plank, yokes fitting around and removable from the brake-beams and slidably and removably mounted in the brackets, respectively, and means for detachably securing the yokes around the brake-beams and connecting them to the brackets.

15 12. A railway truck structure comprising a side-frame, brake-beams, brake-shoes at the ends of the beams, a spring-plank carried by the side-frame, an inward extension on the side-frame underlying the spring-plank, a bracket on the inner end of the extension at each side of the spring-plank, each bracket comprising a pedestal and longitudinally extending arms, yokes removably fitting around and removable from the brake-beams and slidably and removably mounted in the arms, and means for detachably securing the yokes around the brake-beams and connecting them to the brackets.
